REVOLVING TRAY STORAGE UNIT

Bruce Waag, 4 Poplar Place,
Bayshore, N.Y. 11706

Filed Jan. 14, 1971, Ser. No. 106,627

Term of patent 14 years

Int. Cl. D9—03

U.S. Cl. D9—232

FIG. 1 is a front elevational view of a revolving tray storage unit showing my new design;

FIG. 2 is a similar front elevational view, showing certain of the component parts thereof in altered relative position;

FIG. 3 is a top plan view thereof as seen from the upper portion of FIG. 1;

FIG. 4 is a top plan view, as seen from the upper portion of FIG. 2; and

FIG. 5 is a bottom plan view thereof.

I claim:

The ornamental design for a revolving tray storage unit, substantially as shown.
